Primary Examiner — Cynthia Underwood(74) *Attorney, Agent, or Firm* — Dunlap Bennett & Ludwig PLLC(57) **CLAIM**

The ornamental design for a saucer base plate, as shown and described.

DESCRIPTION

FIG. 1 is a perspective top front view of a saucer base plate; FIG. 2 is a front elevation view of the saucer base plate; the rear elevation view, the right elevation view and the left elevation view are mirror images thereof;

FIG. 3 is a top elevation view of the saucer base plate; and, FIG. 4 is a bottom elevation view of the saucer base plate. The broken lines shown in the drawings depict portions of the saucer base plate that form no part of the claimed design.
